WORK GUIDE FOR WOODWORKING MACHINES

**Theron L. Hedgpeth, Oak Park, Ill., assignor to
Duro Metal Products Company, Chicago, Ill.,
a corporation of Illinois**

**Original application May 2, 1935, Serial No.
19,335. Divided and this application Decem-
ber 31, 1936, Serial No. 118,426**

1 Claim. (Cl. 144—253)

The present invention relates to work guides for wood working machines, and is particularly concerned with an improved work guide to be used on shapers or similar tools.

5 The present application is a division of my prior application Serial No. 19,335, filed May 2, 1935, for Wood working tools, which has resulted in the issuance of Patent No. 2,076,511 dated April 6, 1937.

10 One of the objects of the invention is the provision of an improved work guide for shapers which is adapted to serve also as a guard to protect the hands of the user from the cutter, and which is also adapted to provide for the discharge 15 of the shavings or cuttings through the work guide.

Another object of the invention is the provision of an improved work guide for shapers having provisions for adjusting the depth of cut into 20 the work piece.

25 Another object of the invention is the provision of an improved work guide having a rear portion adapted to be adjusted and secured and having a forward portion or section which is adapted to be adjusted with respect to the rear portion after the former has been secured in place.

30 Another object of the invention is the provision of an improved shaper fence or work guide which is capable of inexpensive manufacture and which is so constructed as to avoid clogging by 35 chips.

Other objects and advantages of the invention will be apparent from the following description, 35 in which similar characters indicate similar parts throughout the several views.

Referring to the drawings, of which there are two sheets:

Fig. 1 is a top plan view of a shaper provided 40 with a work guide constructed in accordance with the present invention;

Fig. 2 is an elevational view taken from the top of Fig. 1;

Fig. 3 is a vertical sectional view taken on the 45 plane of the line 3—3 of Fig. 1 looking in the direction of the arrows showing the details of construction of the adjustable front section of the guide; and

Fig. 4 is a vertical sectional view taken on the 50 plane of the line 4—4 of Fig. 1 looking in the direction of the arrows showing the chip discharge opening in the guide.

Referring to Fig. 1, 10 indicates in its entirety the shaper which is provided with a table 11 supported upon a base 12. The base has a suit-

able arrangement for journaling the cutter shaft 12' and a suitable arrangement for raising and lowering the cutter shaft with respect to the top of table 11. The shaft 12' and cutter 13 are arranged concentrically with respect to an aperture 14 in the table top 11.

The shaper is preferably provided with a combined fence and guard 15 which may consist of a cast metal member having a pair of attaching flanges 16, 17 joined by an upwardly projecting 10 guard portion 18. The guard portion 18 comprises a relatively short and wide oval conduit 19 leading from the vicinity of the cutter 13 to the left edge of the table in Fig. 4. The conduit 19 is adapted to discharge the chips which are removed from the work piece 20 by the cutter 13.

In order to provide for the adjustment of the work guide 15 into close relation with the cutter 13, the guard portion 18 is provided with a semi-circular groove 20' which is of sufficient size to 20 receive the cutter 13 without contact when the cutter is elevated to the top of the guard portion 18 and the guide 15 is adjusted into close proximity with the cutter. The guard portion 18 may extend over at 21 behind the cutter while 25 it is narrower at the point 22 to permit room for adjustment of an adjustable guide shoe 23.

Both the attaching flanges 16 and 17 are provided with lower flat engaging surfaces 24, 25 located at the elongated slots 26, 27. The flange 30 16 extends over behind the cutter 13 that is at the left of the cutter in Fig. 1 and has an upwardly extending flange 28 which is at right angles to the plane of the table top 11 and to the plane of the surfaces 24, 25. Vertical flange 28 35 preferably supports a wooden shoe 29 comprising a strip of hard wood which is secured to the flange 28 by one or more screw bolts and nuts 30, all preferably having their heads countersunk in the shoe 29. The flange 17 is of lesser area 40 than the flange 16 terminating at the line 22, previously mentioned, in order to permit room for adjustment of the shoe 23.

The shoe 23 is similar in construction to shoe 29, but it is supported upon a vertical flange 31 45 by means of one or more screw bolts 32. Vertical flange 31 is a part of a cast metal fitting 33 which has a diagonally extending socket 34. The socket 34 is adapted to receive the reduced cylindrical end 35 of an adjustment plunger 36. End 50 35 is secured in place by set screw 37 and by the engagement of the annular shoulder 38 with the fitting 33. The larger cylindrical portion 39 of the plunger 36 is provided with an axially extending slot 40 on its upper side, and this larger 55

cylindrical portion is slidably mounted in a cylindrical bore 41 located in a body 42 carried by attachment flange 17. The body 42 has its bore 41 extending diagonally upward and toward the right in Fig. 1. A threaded member 43 is threaded into a threaded bore which communicates with bore 41 and the reduced cylindrical end 44 of threaded member 43 slidably engages in slot 40 to prevent rotation of the plunger 36. 5

10 Plunger 36 is also provided with an axially extending threaded bore 45 receiving the threaded end 46 of a shaft 47 which is journaled in a counterbore 48 located in the right end of body 42. Shaft 47 has an integral thrust flange 49 located in the bore 41. The outer end of shaft 47 is received in a bore 50 of the crank 51 where it is secured by a cross pin 52 that may be riveted in place. The crank 51 thus serves as a thrust bearing engaging the end of the body 42. 15

20 When the crank 51 is rotated the threaded end 46 in the bore 45 causes the plunger 36 to progress forward or backward. This causes the shoe 23 to be adjusted downward or upward in Fig. 1. The shoe 23 is adapted to engage the flat surface 25 of the work piece 20 as the work piece approaches the cutter 13. The shoe 29 may be so adjusted that it provides engagement for that part of the work piece 20 which has been shaped. 25

The position of the combined guard and work fence 15 is determined by its adjustment on the table top 11 where it may be clamped by the threaded members 53, 54 which thread into the portion 55, 56 in the table 11. Both guides may be simultaneously adjusted and clamped in position by means of the screw bolts 53, 54, thereby saving time in the use of the machine. 30

It will thus be observed that I have invented an improved work guide and guard for wood working tools such as shapers, by means of which the depth of cut may be predetermined and the work may be satisfactorily guided during the 5 shaping operation.

While I have illustrated and described a preferred embodiment of my invention, many modifications may be made without departing from the spirit of the invention, and I do not wish to 10 be limited to the precise details set forth, but desire to avail myself of all changes within the scope of the appended claim.

Having thus described my invention, what I claim as new and desire to secure by Letters 15 Patent of the United States is:

In a wood working machine, the combination of a supporting table with a combined cutter guard and fence, said fence having an attaching flange and a guide flange, and having a chip conduit formed adjacent a cutter carried by said table, said attaching flange having adjustable means for securing it to the table, and a plunger housing carried by said attaching flange, said plunger housing having a bore and a counterbore, 25 with an annular shoulder between said bore and counterbore, a plunger slidably mounted in said bore, a screw shaft having thrust bearings on each end of said counterbore, and rotatably mounted in said counterbore, said screw shaft 30 having threaded engagement with said plunger, and an adjustable guide shoe carried by said plunger and extending in parallel relation with respect to said other guide flange. 35
